(57) **CLAIM**

The ornamental design for a cosmetic package as shown and described.

DESCRIPTION

FIG. 1 is a front perspective view of the cosmetic package showing my new design;

FIG. 2 is a perspective view showing a first component separate from a second component, and showing tops of the first component and the second component removed;

FIG. 3 is a front perspective view of the first component with the top removed;

FIG. 4 is a front elevational view of the first component with the top removed;

FIG. 5 is a rear elevational view of the first component with the top removed;

FIG. 6 is a right side elevational view of the first component with the top removed;

FIG. 7 is a left side elevational view of the first component with the top removed;

FIG. 8 is a top view of the first component with the top removed;

FIG. 9 is a bottom view of the first component with the top removed;

FIG. 10 is a front perspective view of the second component with the top removed;

FIG. 11 is a front elevational view of the second component with the top removed;

FIG. 12 is a rear elevational view of the second component with the top removed;

FIG. 13 is a right side elevational view of the second component with the top removed;

FIG. 14 is a left side elevational view of the second component with the top removed;

FIG. 15 is a top view of the second component with the top removed; and,

FIG. 16 is a bottom view of the second component with the top removed.

(Continued)

The broken lines shown illustrate portions of the cosmetic package that form no part of the claimed design.

1 Claim, 16 Drawing Sheets
